UNITED STATES PATENT OFFICE

SAMUEL HAMMER, OF BROOKLYN, NEW YORK, ASSIGNOR TO UNITED METAL BOX CO.
INC., OF BROOKLYN, NEW YORK, A CORPORATION OF NEW YORK

LATCH MEANS FOR CABINET DOORS

Application filed January 22, 1932. Serial No. 588,083.

This invention relates to latch means for cabinet doors, and has for its general object and purpose to provide a simple and efficiently operating latch for the doors of cabinets in which clothes dryers or other devices may be housed, and in which the door is automatically latched upon closing the same and securely held in closed position against accidental release, together with means for readily effecting the release of the latch which obviates any projection on the face of the cabinet door, and which is so located and arranged as to be quite inconspicuous when the cabinet is closed.

More particularly, my present invention is concerned with an improved latch means for the door of a cabinet clothes dryer of the type shown and described in my pending application for patent Serial No. 581,200, filed December 15, 1931, and in which there is provided a clothes rack support mounted for vertical travelling movement within the cabinet. My invention, in its essentials, comprehends the provision of a latch plate or finger fixed to the inner side of the hinged door of the cabinet and adapted to cooperate with a part of the clothes rack support when the door is moved to closed position, to thereby securely latch and hold the door against opening movement, and which latching engagement of the finger with said support is released in the initial upward vertical movement of the support from its normal position by a manually operable element extending downwardly through the bottom wall of the cabinet.

It is also a further object of the invention to provide an emergency means for moving said rack support out of engagement by the latching finger in the event that said manually operable means for vertically moving the support in the casing should for any reason become inoperative.

It is also an additional object of the invention to provide means mounted on the rack support yieldingly engaging the inner face of the door and operating upon the release of the latching means to project said door outwardly towards its open position.

With the above and other objects in view,

the invention consists in the improved latch means for cabinet doors, and in the form, construction and relative arrangement of its several parts, as will be hereinafter more fully described, illustrated in the accompanying drawing and subsequently incorporated in the subjoined claims.

In the drawing wherein I have disclosed one simple and satisfactory embodiment of the invention, and in which similar reference characters designate corresponding parts throughout the several views,—

Figure 1 is a fragmentary front elevation of a clothes dryer cabinet, the door thereof being partly broken away and illustrating one practical form of my present invention.

Fig. 2 is an enlarged vertical sectional view taken substantially on the line 2—2 of Fig. 1;

Fig. 3 is a fragmentary perspective view of the door showing the latching finger thereof, and

Fig. 4 is a horizontal sectional view taken substantially on the line 4—4 of Fig. 1.

Referring in detail to the drawing, 5 designates the cabinet body which may be of any desired construction, but is preferably stamped from sheet metal and adapted to be mounted either upon the wall face, or within a mortise or recess formed in the wall face. 80 The front open side of this cabinet body is provided with the door 6 hinged along one vertical edge thereof, as indicated at 7.

Within the body of the cabinet, a clothes dryer or other apparatus is housed. Since 85 a detailed description of this apparatus is unnecessary for a full understanding of my present disclosure, only the parts thereof which are essential to such understanding will be herein referred to, though, if desired, 90 a full understanding of such apparatus may be obtained by reference to my co-pending application heretofore referred to.

The clothes dryer includes a support 8 for the relatively adjustable arms 9 from which the articles to be dried are adapted to be suspended. This support is pivotally mounted for vertical swinging movement upon the carriage plate 10 which, in turn, is mounted within the body of the cabinet for vertical 100

travelling movement between the upper and lower ends thereof. The carriage plate, together with the clothes rack support, moves by gravity to a normal position at the lower end of the cabinet, and is raised or elevated to the upper end of the cabinet by means of a rope or other flexible connection 11 with the carriage plate 10, said flexible element extending downwardly through the bottom 10 wall of the cabinet adjacent one vertical edge thereof as shown in the drawing. When the carriage plate 10 is in its normal lowered position, the support 8, together with arms 9, may be raised in a perpendicular position in 15 substantially parallel relation with the carriage plate 10 and with said support and the arms 9 disposed within the open side of the cabinet body. Upon then closing the door 6, the various parts of the clothes dryer are 20 completely concealed as well as housed and protected against injury or the collection of dust and dirt thereon.

It is desirable, of course, in cabinets of this kind, designed for use in private apartments 25 or dwellings, that the cabinet shall detract as little as possible from the appearance of the room, and also that there shall be a minimum of projection of cabinet parts from the face of the wall. To this end, therefore, I 30 have devised an improved latch means for the cabinet door which altogether eliminates any projection whatsoever from the face of the door for the purpose of releasing the latch and moving the door to open position.

35 In the illustrated embodiment of my invention, this door latch means may consist in the latch finger shown at 12, which is in the form of a rigid metal arm which is welded or otherwise permanently fixed to the inner 40 face of the door plate near its lower end and adjacent to its free vertical edge. This latch finger or arm projects at right angles to the plane of the door plate and has a vertically 45 extending edge 13 disposed in spaced parallel relation to the inner face of the door and the obliquely inclined edge 14 extending from the rear edge of the latch finger to the upper end of its forward vertical edge 13.

The latch finger 12 is so located relative 50 to the rack support 8, that when the latter is raised to its vertical position within the open side of the cabinet, upon closing the door 6, the inclined edge 14 of the latch finger is brought into bearing engagement against 55 the lower edge of the support 8 before the door reaches its fully closed position. Upon then applying the requisite pressure against the outer face of the door, this inclined edge 14 of the latch finger forces the support 8 60 and its carriage upwardly within the cabinet until the lower edge of the support 8 rides over the upper terminal of the latch finger, whereupon said carriage and the support will drop by gravity to their normal positions, 65 and the lower edge of the support 8 will be

interposed between the vertical edge 13 of the latch finger 12 and the rear face of the door 6. Thus the door is securely latched and tightly held in its fully closed position. Since this latching means is wholly contained within the body of the cabinet, it is obvious that there is no possibility of the latch being accidentally released as might occur if the same were actuated by a movable part on the face of the door. 70

It will nevertheless be evident that when desired, the door can be very easily and quickly released for movement to its open position, merely by pulling downwardly upon the end of the flexible element 11 which extends 80 through the bottom wall of the cabinet. The carriage plate 10 with the support 8 will thereby be lifted for a sufficient distance to disengage the lower edge of said support from the latch finger 12, so as to permit of 85 the opening movement of the door.

In order to facilitate this easy and quick opening of the door and for also tightly holding the upper edge of the latch finger 12 in engagement with the support 8, I preferably 90 provide upon said support the spring pressed pin 15. While this pin might be mounted upon the support 8 in various ways, I have herein shown a sheet metal cup 16 having its open end securely fixed in the support 8 95 and housing the coiled spring 17 which surrounds a reduced part of the pin 15 projecting through an opening in the closed end of the cup 16.

It will be evident from this description 100 that when the door 6 is moved to its closed position, the rear side of said door before the latter is fully closed comes into bearing contact against the outer end of the pin 15, and forces the same into the cup 16, thereby compressing the spring 17. Thus when the door is fully closed, the expansion pressure of this spring acting on pin 15, is transmitted to the door 6, tending to urge the latter towards an open position and thus hold the edge 13 of the latch finger 12 in bearing contact against the lower edge of support 8. Accordingly, when said support is raised to 110 release the same from engagement with the latch finger, said spring pressed pin 15 will immediately act to move the door towards its open position, so that upon the release of the pulling strain on the flexible element 12 and the descent of the support 8 to its normal position, the latch finger 12 will be out 120 of the path of movement of the support. The door may then be manually swung to its full open position at one side of the cabinet body. 125

From the foregoing description considered in connection with the accompanying drawing, the construction, manner of operation and several advantages of my present invention will be clearly and fully understood. It will be seen that I have devised a very 130

simple and effective latching means for the doors of cabinets of this type, and which eliminates the objectionable projection of knobs, operating handles or other parts necessary to effect the release of the latching means, from the face of the cabinet door. When the door is closed, the finger piece or hand grasp attached to the flexible element 11 is positioned closely adjacent to the bottom wall of the cabinet so that it will be quite inconspicuous. Although this use of the flexible operating element which is provided for raising and lowering the carriage plate 10 and rack support within the cabinet for the purpose of releasing the door latch, will usually be found quite sufficient, it is nevertheless just possible that this flexible element might break or become detached from connection with the carriage plate 10, so that in such event, if the cabinet door were closed, it could not be opened without serious damage thereto. Although this possibility is somewhat remote, I nevertheless herein suggest the provision of an emergency means whereby the carriage plate and the rack support may be lifted sufficiently to release the latching finger on the door. As shown, this emergency releasing means may conveniently consist in the provision of the pin 18 suitably fixed at its upper end to the lower end of the carriage plate 10 and projecting downwardly through the opening 19 in the bottom wall of the cabinet body, when said carriage plate is in its normal lowered position. This pin also will be quite inconspicuous, and need only project through the opening 19 for a distance sufficient to raise the lower edge of support 8 above the upper end of the latch finger 12 when an upward pressure is applied to the lower end of the pin. However, it is to be understood that this emergency latch releasing means is not essential, and may be eliminated if desired.

It will be apparent from the above description that the several elements comprised in my improved latch means for a cabinet door are of very simple mechanical form, and may be readily applied in the manufacture of a dryer cabinet, without materially increasing production cost. The device is also exceedingly durable, as well as highly efficient and serviceable for the purpose in view. Although I have herein shown and described one simple and practical embodiment of my improved cabinet door latch, it is nevertheless to be understood that the essential features thereof might be incorporated in various other alternative, structural forms, and I therefore reserve the privilege of resorting to all such legitimate changes in the form, construction and relative arrangement of the several elements as may be fairly embodied within the spirit and scope of the appended claims.

65 I claim:

1. In combination with a cabinet having a hinged door, and a member mounted within said cabinet for vertical movement; a latch finger projecting from the rear face of said door for cooperative latching engagement with said member when the latter is in its lowermost position within the cabinet, means extending exteriorly of the cabinet for moving said member upwardly therein out of engagement with the latch finger, and spring means on the vertically movable member placed under compression by the door when moved to closed position and acting against said door to urge the same towards an open position upon the release of said latch finger. 70
2. In combination with a cabinet having a hinged door, and a clothes dryer mounted within said cabinet for vertical travelling movement having a flexible operating element connected therewith; a latch finger fixed to the rear face of said door to cooperate with a part of the clothes dryer within the cabinet and latch said door in its fully closed position, said latch finger being released upon operation of said flexible means to move the dryer upwardly within the cabinet body, and means movable with the dryer having resilient bearing engagement against the inner face of the door to urge the same towards its open position upon the release of the latch finger. 75
3. In combination with a cabinet having a hinged door, and a clothes dryer mounted therein, including a vertically movable carriage and a clothes rack support mounted on said carriage, and a flexible operating member for said carriage extending exteriorly of the cabinet body; a latch finger fixed to the rear face of the door and cooperating with said clothes rack support to latch the cabinet door in a closed position, said carriage and the rack support being adapted to be lifted from a normal position in the lower end of the cabinet by means of said flexible operating member to release the latch finger, and an auxiliary emergency releasing means fixed to the carriage and projecting below the cabinet body, whereby said carriage and the rack support may be lifted independently of said flexible operating member. 80
4. In combination with a cabinet having a hinged door, an article supporting device within the cabinet, and means for moving said device from the lower to the upper end of the cabinet, a latch finger projecting from the rear face of the door cooperating with a part on said device in the lowermost position thereof to latch said door in closed position, said latch finger being released by the operation of said means to move the device upwardly in the cabinet. 85
5. In combination with a cabinet having a hinged door, an article supporting device within the cabinet, including a carriage and 90

means for moving said carriage from the lower to the upper end of the cabinet, a latch finger projecting from the rear face of the door cooperating with a part on said carriage in the lowermost position thereof to latch said door in closed position, said latch finger being released by the operation of said means to move the carriage upwardly in the cabinet, and additional means fixed to the carriage and projecting exteriorly of the cabinet for manual operation to lift said carriage to latch releasing position independently of said first named means.

6. In combination with a cabinet having a hinged door, an article supporting device

within the cabinet, and means for moving said device from the lower to the upper end of the cabinet, a latch finger projecting from the rear face of the door cooperating with a part on said device in the lowermost position thereof to latch said door in closed position, said latch finger being released by the operation of said means to move the device upwardly in the cabinet, and additional means on said device, operating upon release of the latch finger, to urge the door toward open position.

In testimony that I claim the foregoing as my invention, I have signed my name hereto.

SAMUEL HAMMER.
